UNITED STATES PATENT OFFICE.

ERASTUS E. WINKLEY, OF LYNN, MASSACHUSETTS, ASSIGNOR TO UNITED SHOE MACHINERY CORPORATION, OF PATERSON, NEW JERSEY, A CORPORATION OF NEW JERSEY.

METHOD OF FORMING STACKS OF WEDGE LIFTS.

1,416,085.

Specification of Letters Patent. Patented May 16, 1922.

Original application filed January 22, 1917, Serial No. 143,738. Patent No. 1,352,492, dated September 14, 1920. Divided and this application filed June 28, 1920. Serial No. 391,237.

To all whom it may concern:

Be it known that I, ERASTUS E. WINKLEY, a citizen of the United States, residing at Lynn, in the county of Essex and State of Massachusetts, have invented certain new and useful Improvements in Methods of Forming Stacks of Wedge Lifts; and I do hereby declare the following to be a full, clear, and exact description of the invention, such as will enable others skilled in the art to which it appertains to make and use the same.

This invention relates to methods of forming stacks of wedge lifts of sheet material, and it has special reference to such lifts as are cut from a piece of stock, or are otherwise formed, or operated upon, and then delivered in face-to-face stacked relation, ready for transferral to other machines.

The invention, although not so restricted, is particularly applicable to wedge-lifts such as are used in the manufacture of shoe-heels, and which may be cut from transversely tapering strips and then arranged and delivered in stacks, for the sake of compactness in storage, or convenience in handling, or in the subsequent feeding of the lifts by the feed mechanisms of other machines, such as automatic heel building machines.

Articles which are wedge shaped or tapering in form will not stack properly to any material height when lying loosely one upon another and all in similar positions with respect to their tapers, or their thick and thin ends. However, if they are arranged in alternate or reverse relation—that is, with their thick and thin ends alternating, they may be stacked to any desired height and may be successfully fed one at a time from one end of the stack.

Such an arrangement or stack of wedge lifts is particularly important when used in connection with a magazine and feed mechanism of an automatic heel building machine, such for instance, as disclosed in Letters Patent of the United States Nos. 1,352,745 and 1,352,746 granted September 14, 1920, to Fred V. Hart. In both of these structures, the lifts are stacked in alternate relation

with respect to their tapers, although the lifts in the stack of the latter patent are so disposed that their analogous faces are all directed the same way, while those of the

former patent have the analogous faces of adjacent lifts in reverse relation or in contacting engagement.

One of the objects of the present invention is to devise a simple and expeditious method of forming stacks of wedge lifts from transversely tapering strips of sheet material from which lifts are successively cut and then progressively arranged in a stack in reverse or alternate relation with respect to their thick and thin ends.

Another object of the invention is to devise a method of the character indicated which shall also result in a stack in which the analogous faces of all of the blanks or articles are directed the same way, such a stack being especially adapted to be handled and fed in an automatic heel building machine having a magazine and feed mechanism of the type shown and described in said patent No. 1,352,746 hereinbefore referred to.

These and other objects and features of the invention will become apparent from the following description of the invention in connection with the apparatus illustrated in the accompanying drawing; of which the single figure is a partially diagrammatic perspective view of apparatus through the agency of which the present invention may be practiced with facility and rapidity.

Those skilled in the art will, of course, understand that the method of the present invention is entirely independent of the apparatus illustrated, which is shown merely as an exemplification of one manner in which the invention may be carried out conveniently. The particular apparatus, chosen for illustrative purposes, is similar to that shown and described in detail in applicant's Letters Patent of the United States No. 1,352,492 granted September 14, 1920, of which the present application is a division. Inasmuch as the apparatus illustrated forms no part of the present invention and, moreover, is set forth completely in the present application to which reference has been made, only a brief general description thereof will be given herein.

Wedge lifts utilized in building shoe-heels are usually cut from transversely tapering strips of sheet material which are conveniently formed by splitting a strip of uniform

thickness in a plane extending diagonally through the lateral edges thereof. A strip thus formed generally has one face at right angles to the surface of its thick lateral edge 5 and another longer face inclined thereto.

In carrying out the method of the present invention, as illustrated in the accompanying drawing, such a transversely tapering strip S is fed step-by-step by means of a 10 reciprocating feed dog 10 from a magazine 12, containing a stack of similar strips, beneath a suitable reciprocating cutter 14. The cutter 14, in this instance, is in the form 15 of a knife which serves to cut polygonal wedge lifts W of the desired width successively from each strip as it is fed. It will be noted that a lift formed in this manner will have one face at right angles to the surface of its thick edge and another face 20 inclined thereto, so that the latter face will be the longer of the two.

In building heels, it is desirable that wedge lifts be positioned with their longer faces directed toward the heel seat thereof 25 and, therefore, it is necessary that the wedge lifts be stacked in the magazine of the heel building machine in such manner that they may be successively fed and presented for assembly with other heel lifts in this position. The method of the present invention 30 accomplishes this result in the following manner.

Immediately after a lift W is cut from the strip S which rests upon its shorter 35 face, it is fed laterally in the direction of its thin end into one of a plurality of stirrup-like carriers 16 by means of a suitable reciprocating pusher 18 that engages the thick end of the lift.

40 The carriers 16 are of like construction and are conveniently made of sheet metal bent into the proper shape. The horizontal bottom plate 20 of each carrier lies in the plane of the cut lift so that the lift may 45 be easily pushed into the carrier where it rests upon the bottom plate thereof. The carriers 16 are suspended from the respective ends of a horizontal supporting arm 22, one carrier being pivotally mounted 50 thereon while the other is fixed thereto. Intermediate its ends the supporting arm 22 is 55 carried by and secured to a vertical shaft 24 that is rotatably mounted in a sleeve 26 forming a part of a supporting bracket 28.

After a lift is introduced by the pusher 18 into one of the carriers 16, the shaft 24 is given a half-rotation so as to bring the loaded carrier to a position adjacent a receiver 30 and replace it with the empty carrier. For this purpose a pinion 32 is 60 fixed to the upper end of the shaft 24 and meshes with a rack 34 which is adapted for reciprocatory movements to turn the shaft and therefore the carriers, first in one

direction and then in the other, through successive half-rotations in opposite directions.

The pivotally mounted carrier 16 into which a lift is about to be loaded, as illustrated in the drawing, is provided with a 70 pinion 36 which meshes through an idler gear 38 with a pinion 40 which is fixedly secured to the sleeve 26. Therefore, as the rack 34 rotates the shaft 24, supporting arm 22 and associated carriers 16 through 75 a half-rotation to transfer the lift in its own plane to a position adjacent the receiver 30, the pinions 36 and 40, together with the idler gear 38 serve to impart a corresponding half-rotation to the pivotally 80 mounted carrier 16 and to the lift being transferred thereby. Thus, the transferred lift in the pivotally mounted carrier 16 occupies a position similar to that which it 85 occupied before the transferral was effected. 85

On the other hand, any lift which is loaded into the carrier 16 which is fixed to the supporting arm 22 is rotated through a half-turn in its own plane during the transfer movement, so that such lift is reversed 90 in position with respect to its taper or its thick and thin ends.

As the lifts are successively transferred by the carriers 16, every alternate lift being 95 reversed end-for-end, the lifts are removed from the carriers and swung upwardly into the receiver 30 by means of an oscillatory lifter arm 42 which is fixed to a periodically 100 operated rock shaft 44 and which swings upwardly through recesses 46 in the bottom plates 20 of the carriers in such manner as to raise the lifts into vertical position in the receiver 30 where they are progressively stacked and retained by means of 105 resilient detents 48 and 50.

It will be apparent that through the operation of the mechanism described, the wedge lifts W which are successively cut from the tapering strips S are progressively transferred and delivered to the receiver 30 in 110 stacked relation in such manner that the lifts are reversed in position with respect to their tapers or thick and thin ends, while their analogous faces are all directed in the same way—that is, all of the longer 115 faces will point in one direction and all of the shorter faces in the other. The lifts so stacked may then be removed from the receiver, still in stacked relation, and conveniently introduced into a magazine of a 120 feed mechanism of a heel building machine or any other machine adapted to operate upon the successive lifts.

In certain aspects of the present invention, the steps of feeding the tapering strips 125 and cutting lifts therefrom successively may be omitted, and a series of lifts that may have been previously cut, or otherwise formed, or operated upon, may be fed all in similar positions into the carriers and 130

subsequently transferred and delivered in stacked relation in the manner set forth. Furthermore, although for illustrative purposes, the present method has been described 5 in connection with wedge shaped polygonal heel lifts, it should be understood that the invention is not in any way restricted to the handling of such blanks, but is generally applicable to any character of wedge shaped 10 articles or blanks of sheet material.

The nature of the invention having been set forth, that which is claimed as new is:

1. The method of forming a stack of wedge articles which includes feeding a succession 15 of wedge articles in similar positions, successively transferring said wedge articles to another position and turning the alternate articles end-for-end in substantially their own planes during the transfer- 20 ral, and stacking the transferred articles with their thick and thin ends alternating.

2. The method of forming a stack of wedge articles which includes feeding a succession of wedge articles in similar positions, and stacking said articles in face-to- 25 face relation with their thick and thin ends alternating and their analogous faces directed the same way.

3. The method of forming a stack of 30 wedge articles which includes feeding a succession of wedge articles in similar positions, reversing the position of every alternate article with respect to its taper, and stacking said articles with their thick and 35 thin ends alternating and their analogous faces directed the same way.

4. The method of forming a stack of wedge articles from a transversely tapering strip of sheet material which includes 40 cutting wedge articles successively from the strip, and progressively stacking said arti-

cles as they are cut in face-to-face relation with their thick and thin ends alternating.

5. The method of forming a stack of wedge articles from a transversely tapering 45 strip of sheet material which includes intermittently and longitudinally advancing the strip, successively cutting wedge articles therefrom, and progressively manipulating said articles to bring them into 50 stacked relation with their thick and thin ends alternating.

6. The method of forming a stack of wedge articles from a transversely tapering 55 strip of sheet material which includes cutting wedge articles successively from the strip, and progressively stacking said articles as they are cut in face-to-face relation with their thick and thin ends alternating and their analogous faces directed 60 the same way.

7. The method of forming a stack of wedge articles which includes feeding a succession of said articles in similar positions, turning the alternate articles end for end 65 while still maintaining the analogous faces of all the articles pointing in the same direction, and stacking the articles with the analogous faces all pointing toward one end of the stack.

8. The method of forming a stack of wedge articles the two faces of which differ from each other in certain characteristics, which includes feeding a succession of said articles with their thick ends all directed 70 one way, reversing the direction of said thick ends on alternate articles of said succession of articles, and then stacking said articles with their analogous faces all directed the same way.

ERASTUS E. WINKLEY.
